UNITED STATES PATENT OFFICE.

MARVIN C. POST, OF BROOKFIELD, MISSOURI.

CARPENTER'S SQUARE.

No. 870,584.

Specification of Letters Patent.

Patented Nov. 12, 1907.

Application filed April 15, 1907. Serial No. 368,198.

To all whom it may concern:

Be it known that I, MARVIN C. POST, a citizen of the United States, residing at Brookfield, in the county of Linn and State of Missouri, have invented certain new 5 and useful Improvements in Carpenters' Squares, of which the following is a specification.

My invention relates to carpenters' tools and refers especially to that class of devices termed folding squares.

10 The chief objects of my improvement are to provide a connecting hinge for the limbs or blades of an ordinary square that will enable the said blades to be folded upon each other until they lie parallel and in apposition, thus permitting the tool to be conveniently 15 carried in a box or chest; to furnish a strong hinge so constructed as to preserve the proper relation of the blades with reference to their mutual plane; and to provide locking means for retaining the parts in their extended or operative position, said locking means 20 having permanent connection with the instrument thus preventing their loss or misplacement.

Further objects of my invention are to produce a folding square that will present a continuous edge along either margin when in extended position and in 25 which both internal and external angles are intact when the square is in its operative position.

I accomplish the above objects by the employment of the device illustrated in the accompanying drawing which forms a part of this specification and in which:

30 Figure 1 is a side view of a portion of a carpenter's square to which is applied my improved method of joining the blades so that the latter are adapted to be folded together, or locked in extended position; Fig. 2 shows the parts of the square in folded position; Fig. 3 35 is an edge view of the joint ends of the separated members, and Figs. 4 and 5 are views of the pivot screw and one of the locking rivets, respectively.

Referring to the drawing in detail, the numeral 6 indicates the larger and 7 the smaller blade of a carpenter's square, the dimensions of which, as well as the 40 graduations marked thereon, are the same as in one of ordinary rigid construction. Upon opposite sides of the blades and formed integral therewith are hinge joints or ears 8, said ears being constructed by removing one half the thickness of the stock as shown at 9 by 45 milling or other available method of machining. As shown in the drawing, the ear which is integral with the short blade 7 projects from its side to correspond with the companion ear of the long blade 6, extending 50 from the inner edge of said blade 7 to a distance equal to a diameter of said ear. The ear formed upon the longer blade 6, touches the inner margin of said blade, and as the diameter of the ear is less than the width of the said blade 6 a projection or shoulder 9^a is formed on 55 both blades, which engage to form a limiting stop when the members are extended. This construction has the

advantage of making the longer limb 6 shorter than it would otherwise be, such shortening being equal to the width of the blade 7, and the folded device will thus take up that much less space in length when placed in 60 the chest or kit. At the center or curvature of the ears a hole is drilled and countersunk on both sides of the assembled parts to receive a pivot which may be a simple rivet headed flush with the surface on either side to form a center upon which the blades may turn. 65 I prefer, however, to make this center in the form of a screw 10 with a lock nut 10^a to take up lost motion, both the head and nut being furnished with slots to receive a screw driver.

Upon opposite sides of the instrument and diametrically across the ears are located locking rivets 11 each rivet having a head shaped like that of a screw to fit a countersunk hole 12 in the blade one edge of the said head being cut away, as shown at 13, to permit the head to pass the margin of the ear when said rivet is given a 75 half turn from its locking position by a screw driver, thus permitting the device to be folded as shown in Fig. 2. The side of the rivet head opposite to the mutilation 13, is received in a notch 14 cut in the periphery of the ear with the same operation that forms the counterbore 14.

It will be understood that the rivets and pivot screw will be formed with their heads flush with the metal so that the sides of the tool will present smooth surfaces.

When the square is expanded to its operative position 85 and the locking rivets turned until their intact margins engage the notches 14 the shoulders 9 being in firm engagement with each other, the limbs of the instrument will be practically as rigid and immovable as if made 90 of a single piece.

Having thus described my invention I claim:—

1. A folding square composed of two blades pivotally connected, one blade having a shouldered lateral hinge member and the other blade furnished with a shouldered end hinge member, said members having registering 95 notches, locking rivets secured to said blades respectively and on opposite sides of the square, and adapted to engage the notches in the margins of said hinge members, each of said rivets having a mutilated head to permit the latter when turned to release its respective hinge member and 100 allow the said blades to be folded.

2. A folding square, including a larger blade having a hinge member projecting from its end, a smaller blade furnished with an integral lateral hinge member, said members having registering notches, a pivot connecting said 105 members and locking rivets secured to said blades and adapted to engage the notches in the margins of said hinge members, each of said rivets having a head cut away upon one side to permit the latter when turned to release its respective hinge member and allow the said blades to be 110 turned upon the connection pivot.

In testimony whereof I affix my signature in the presence of two witnesses.

MARVIN C. POST.
